(57) **CLAIM**

The ornamental design for an ant moat for a bird feeder, as shown and described.

DESCRIPTION

FIG. 1 is a front perspective view of an ant moat for a bird feeder embodying my new design.

FIG. 2 is a right elevation view of the ant moat for a bird feeder, a left elevation view being substantially the same.

FIG. 3 is a front elevation view of the ant moat for a bird feeder, a back elevation view being substantially the same.

FIG. 4 is a top plan view of the ant moat for a bird feeder.

FIG. 5 is a bottom plan view of the ant moat for a bird feeder.

FIG. 6 is a front perspective view of the ant moat for a bird feeder with the hanger in a down position.

FIG. 7 is a right elevation view of the ant moat for a bird feeder with the hanger in the down position; a left elevation, a front elevation, and a back elevation being substantially similar; and,

FIG. 8 is a top plan view of the ant moat for a bird feeder with the hanger in the down position.
